CLAIM

The ornamental design for a flag holder for a boat, as shown and described.

DESCRIPTION

FIG. 1 is an elevational front view of a flag holder for a boat in accordance with the present invention;

FIG. 2 is an elevational left view of the flag holder for a boat in FIG. 1;

FIG. 3 is an elevational right view of the flag holder for a boat in FIG. 1;

FIG. 4 is an elevational rear view of the flag holder for a boat in FIG. 1;

FIG. 5 is a top plan view of the flag holder for a boat in FIG. 1;

FIG. 6 is a bottom plan view of the flag holder for a boat in FIG. 1; and,

FIG. 7 is a perspective view of the flag holder for a boat in FIG. 1.

The broken lines in the drawings depict portions of the flag holder for a boat, namely flag clips, that form no part of the claimed design.

1 Claim, 6 Drawing Sheets
